[57] CLAIM

The ornamental design for a two-sided message mat, as shown and described.

DESCRIPTION

FIG. 1 is a front elevational view of the two-sided message mat showing our new design;

FIG. 2 is a rear elevational view thereof;

FIG. 3 is a right side view thereof;

FIG. 4 is a left side view thereof;

FIG. 5 is a top plan view thereof; and,

FIG. 6 is a bottom plan view thereof.

The cross hatch shading partially shown in FIGS. 1 and 2 represents a conventional material and said shading is also understood to continue across the areas shown in the aforementioned figures.
